US0D1007144S

(12) United States Design Patent (10) Patent No.: US D1,007,144 S
(45) Date of Patent:  Dec. 12, 2023

(54) HANDBAG

(71) Applicant: Salvatore Ferragamo S.p.A., Florence (IT)

(72) Inventor: Francesca Murri, Rome (IT)

(73) Assignee: SALVATORE FERRAGAMO S.P.A., Florence (IT)

() Term: 15 Years

(21) Appl. No.: 35/514,626

(22) Filed: Jun. 14, 2022

(80) Hague Agreement Data

Int. Filing Date: Jun. 14, 2022

Int. Reg. No.: DM/221601

Int. Reg. Date: Jun. 14, 2022

Int. Reg. Pub. Date: Jul. 1, 2022

(30) Foreign Application Priority Data

Feb. 21, 2022 (EM) 008868137-0001

Feb. 21, 2022 (EM) 008868137-0002
